BOBBIN WINDER MECHANISM

Charles E. Colegrove, Lakewood, Ohio, assignor to White Sewing Machine Corporation, Cleveland, Ohio, a corporation of Delaware

Application May 14, 1945, Serial No. 593,734

11 Claims. (Cl. 112—218)

1

This invention relates to a bobbin winder mechanism for a sewing machine.

An object of the invention is to provide a bobbin winder mechanism for a sewing machine which is of improved construction and design and in which the actuating mechanism for the bobbin winder is entirely enclosed and housed within the sewing machine head.

Another object is to provide an improved and novel bobbin winder mechanism for a sewing machine wherein the bobbin spindle of the mechanism is mounted on a fixed axis and does not move when the actuating mechanism for the spindle is brought into or out of operative relationship with respect to the drive for the bobbin winder mechanism.

Another object of the invention is to provide a bobbin winder mechanism for use with a sewing machine that employs a belt extending from a motor driven pulley on the underside of the sewing machine bed plate to a pulley mounted on the main drive shaft in the upper horizontal arm section of the sewing machine and which bobbin winder mechanism is driven from said belt and is concealed together with the belt in the vertical column of the sewing machine arm.

Another object of the invention is to provide a bobbin winder mechanism for use in sewing machines which have a removable closure or cover plate for concealing the driving connection between a power source beneath the bed plate and the main drive shaft in the horizontal arm section of the sewing machine and which bobbin winder mechanism is mounted on and carried entirely by said closure or cover plate.

Further and additional objects and advantages not hereinbefore specified will become apparent hereinafter during the detailed description of an embodiment of the invention which is to follow.

Referring to the accompanying drawing illustrating said embodiment of the invention,

Fig. 1 is a fragmentary front elevational view of a sewing machine arm or head with certain portions broken away to disclose the bobbin winder mechanism.

Fig. 2 is an end elevational view of the sewing machine head shown in Fig. 1, with a portion of the removable closure or cover plate broken away to show certain parts of the bobbin winder mechanism carried thereby, the parts of the bobbin winder mechanism being shown in their relationship during the operation of the bobbin winder mechanism.

Fig. 3 is a view similar to Fig. 2 but with more of the removable cover plate or closure broken

2

away and with the parts of the bobbin winder mechanism shown in the relationship they occupy when the bobbin winder mechanism is not being operated, certain parts of the drive from the power source to the main drive shaft being omitted in this view as they form no part of the present invention, and

Fig. 4 is an end elevational view similar to Fig. 3 with the removable closure or cover plate shown in its entirety.

Referring to the drawings and particularly Fig. 1, the bobbin winder mechanism embodying the present invention is shown as applied to a sewing machine having a drive wherein a double belt is employed, but it should be understood that the present disclosure is merely by way of illustration and that the bobbin winder mechanism embodying the present invention could be applied to a sewing machine having a single belt drive or any other suitable drive.

The sewing machine disclosed comprises a bed plate 10 having a head, gooseneck or arm indicated generally at B and including a vertical portion or column 11 and a horizontal portion 12, it being understood that said latter portion mounts at its free end the needle bar, pressure foot and other mechanism well understood in the art. The main drive or needle bar shaft 13 is rotatably mounted in suitable bearings in the horizontal portion 12 of the arm and one of these bearings, indicated at 14, is carried in a vertically extending web, transverse partition wall or side wall 15 of the column. The wall 15 provides a cavity in the end of the sewing machine arm and separates the belt drive mechanism to the main drive shaft 13 from the operative connections between the shaft 13 and the stitch forming mechanism of the sewing machine and which connections are in the vertical column. The main drive shaft 13 extends into the cavity referred to and beyond the bearing 14 and has fixed thereto a flanged sleeve 16. An upper pulley 17 is mounted for free rotation on the sleeve 16 and is provided in this instance with an integral hand wheel portion 17a. A nut 18 is screwed onto the threaded end of the sleeve 16 and contacts a washer 19 which in turn engages one or more balls 20 located between the washer 19 and a second washer 21 carried by the sleeve 16 and engaging one end of the hub of the upper pulley 17.

It will be seen that when the nut 18 is screwed onto the sleeve 16 the hub of the upper pulley 17 will be firmly held between the flange of the sleeve 16 and the washer 21 with a friction driving connec-

tion and thus when the pulley rotates the sleeve 16 and shaft 13 will rotate therewith. When the nut 18 is unscrewed to loosen the same and to disengage the driving connection between the sleeve 16 and the upper pulley 17 said pulley will rotate freely on the sleeve 16, at which time the shaft 13 will be idle.

A main drive motor 22 is supported beneath the bed plate 10 and is connected preferably by a flexible driving connection to a shaft 23 mounted in suitable bearings beneath the bed plate and has fixed thereto a small pulley 24. A supporting bracket or plate 25 is adjustably mounted on the outer side of the partition wall 15 by means of threaded studs carried by said wall and extending through arcuate slots 26 in the opposite ends of the plate 25 and with the said studs provided with clamping nuts.

The supporting plate or bracket 25 carries a shaft on which is rotatably mounted a double pulley composed of a large pulley 27 and a small pulley 28. An endless belt 29 extends around the pulleys 24 and 27 and a second endless belt 30 extends around the pulleys 28 and 17. The construction thus far described forms per se no part of the present invention and need not be more fully explained.

The cavity in the sewing machine arm outwardly of the partition wall 15 is enclosed by a removable cover or closure plate 31 which is secured to the sewing machine arm by suitable means such as removable securing screws. The removable cover or closure plate 31 is shaped to conform to the configuration of the sewing machine arm and is provided adjacent its upper end with an opening which surrounds the hand wheel portion 17a of the upper pulley 17, as indicated in Fig. 1, wherefore when the securing screws or other means are removed the closure or cover plate 31 can be bodily separated from the sewing machine arm.

The bobbin winder mechanism embodying the present invention is mounted on and carried entirely by the removable cover or closure plate 31, that is when said plate is detached from the sewing machine arm the bobbin winder mechanism moves with the plate as a unit. The arrangement is such that when the plate and bobbin winder mechanism are assembled on the sewing machine arm said mechanism is concealed by the closure plate or cover and is housed within the cavity between the latter and the partition wall 15.

The removable closure or cover plate 31 is provided with a hub 32 which rockably mounts a sleeve 33 formed integral with a bell crank lever L at the junction of the angularly disposed arms 34 and 35 of said bell crank lever. A bobbin winder spindle 36 is rotatably mounted in the sleeve 33 of the bell crank lever L and said spindle has fixed to its inner end on the inner side of the plate 31, i. e., its left hand end as viewed in Fig. 1, a gear 37. The right hand or outer end of the spindle 36 has fixed thereto a hub 38 which has a reduced portion on which the bobbin 39 can be mounted.

The arm 34 of the rockable bell crank lever L extends upwardly and has fixedly mounted in its free end a stud 40 which rotatably mounts a gear 41 that has a sleeve on which is fixed a drive element or pulley 42 for the bobbin winder mechanism and so located that it can be brought into operative contact with the belt 30. The gear 41 meshes with the gear 37 on the spindle 36 and it will be seen that when the bell crank lever

L rocks, said gear 41 will roll around the circumference of the gear 37.

It will also be seen that when the pulley 42 is in driving contact with the belt 30 and is being rotated thereby the gear 41 will drive the gear 37 to rotate the spindle 36 and the bobbin 39 which may be mounted thereon.

The cover or closure plate 31 is provided with a hub through which a rock shaft 43 extends. The rock shaft 43 exteriorly of the removable cover plate 31 has fixed thereto a finger 44 for a purpose later to be explained, see Figs. 2 and 4. The rock shaft 43 on the inner side of the cover plate 31 has fixed thereto one end of a lever arm 45 which projects outwardly of the front side of the sewing machine through a suitable vertically extending slot 46 at the joint between the cover plate 31 and the sewing machine arm. The outer end of the lever arm 45 is provided with a knob 47 which can be grasped by the operator when manually moving the lever arm 45.

A bell crank 48 is rockably mounted on the inside of the cover plate 31 on a stud 49 carried by the cover plate and said bell crank lever 48 has an arm 50 extending toward the rear of the sewing machine, an angular arm 51 extending in a generally upwardly direction and a short arm 52 extending toward the front of the sewing machine. The arm 51 of the bell crank 48 is provided with a slot having a straight portion 53 and an arcuate portion 54, the radius of which is struck from the center of shaft 43.

The lever arm 45 on its lower edge has a downwardly extending projection which is provided with a laterally extending pin 55 that projects into the slot in the arm 51 of the bell crank 48, for a purpose later to be explained. The arm 52 of the bell crank 48 is connected to the lower end of a tension spring 57, the upper end of which spring is connected to a fixed pin 58 carried by the cover plate 31 and projecting from the inner side of said plate. The spring 57 continuously tends to move the parts in a direction such that the pulley 42 is moved out of engagement with the belt 30.

The rear end of the arm 50 of the bell crank 48 is pivotally connected to the lower end of a link 59 and said link is provided at its upper end with a longitudinally extending slot 60 which receives a pin 61 carried by the rear end of the arm 35 of the bell crank L; in other words, the link 59 is pivotally connected at its opposite ends with the arms 50 and 35 of the bell cranks 48 and L, there being a lost motion connection between the link and the arm 35 due to the slot 60 and pin 61.

A compression spring 62 is mounted on the link 59 and has its lower end engaging an abutment plate that contacts the rear end of the arm 50, while the upper end of the spring 52 engages a slidably abutment plate which contacts the rear end of the arm 35. The compression spring 62 tends to maintain the arms 50 and 35 and the link 59 in the relationship shown in Fig. 2, that is, there is provided an overtravel of the bell crank L beyond that which is required to cause the pulley 42 to move from inoperative position into contact with the belt 30. The resilience of the spring 62 is such that the spring will begin to compress immediately upon driving contact between the belt 30 and the pulley 42, irrespective of the position of the belt because of belt adjustment or slackness. This arrangement provides for the proper functioning and movements

of the bobbin winder mechanism regardless of the exact position of the driving belt 30.

When it is desired to operate the bobbin winder mechanism the nut 18 on the sleeve 16 is loosened to disconnect the friction driving engagement between the pulley 17 and the sleeve 16 and main shaft 13. The parts of the bobbin winder mechanism should at this time be in their inoperative relationship as shown in Fig. 3 and wherein the pulley 42 is out of engagement with the belt 30, the pin 55 is at the upper end of the straight portion 53 of the slot in the arm 51 and the lever arm 45 is in its upper position. The bobbin 39 is placed on the hub 38 on the bobbin spindle 36 and several turns of the thread 63 are made around the bobbin to cause the winding of the thread on the bobbin to start. The thread 63 extends from a spool of thread 64 which is mounted on a vertically extending spindle 65 projecting from the bed plate 10 and said thread passes from said spool through a thread guide 66 to the bobbin.

The lever arm 45 is moved from its upper position shown in Fig. 3 to its downward position shown in Fig. 2. This movement of the lever arm causes the pulley 42 to come into driving contact with the belt 30. As the lever arm 45 moves downwardly the pin 55 travels downwardly in the inclined straight portion 53 of the slot in the arm 51 of the bell crank 48, with a resultant rocking movement of the bell crank 48 in an anticlockwise direction as viewed in the drawings. This rocking movement of the bell crank 48 is imparted to the bell crank L through the compression spring 62 on the link 59 and said bell crank L rocks in a counterclockwise direction until the pulley 42 is in driving contact with the belt 30. The engagement of the pulley 42 with the belt 30 occurs approximately at the time that the pin 55 reaches the junction between the straight slot 53 and the arcuate slot 54, at which time the lever arm 45 has been moved only partially from the position shown in Fig. 3 toward the position shown in Fig. 2. The further downward movement of the lever arm 45 causes the pin 55 to travel toward the lower end of the arcuate slot 54 and any further slight counterclockwise rocking movement imparted to the bell crank 48 by the movement of the pin 55 in the arcuate slot 54 results in a compression of the spring 62 and a relative movement of the pin 61 at the rear end of the arm 35 of the bell crank L downwardly in the slot 60 of the link 59. The spring 62 maintains the pulley in driving contact with the belt 30 under spring pressure. When the pin 55 is in the arcuate slot 54 it locks the bell crank 48 against rocking movement in a clockwise direction under the action of the tension spring 57, and hence the parts are maintained in the relationship wherein the pulley 42 is in driving engagement with the belt 30.

As the lever arm 45 is moved downwardly to cause the pin 55 to travel downwardly in the arcuate slot 54 the arm or pressure finger 44 fixed to the outer end of the shaft 43 rocks in a counterclockwise direction from the position shown in Fig. 4 into the position shown in Fig. 2, at which latter time the finger or arm 44 contacts the barrel of the bobbin. The motor 22 may now be started to cause rotation of the pulleys 24, 27, 28 and 17 and movements of the belts 29 and 30 which extend around said pulleys. However, at this time the main shaft 13 will not be rotated as it will be recalled the driving connection between the pulley 17 and said shaft is disengaged.

The movement of the belt 30 causes rotation of the pulley 42 and gear 41 with a resultant rotation of the gear 37, spindle 36, hub 38 and bobbin 39. As the bobbin rotates the thread 63 is wound thereon and as the thread begins to build up on the bobbin the arm or finger 44 moves in a clockwise direction and effects through the shaft 43 an upward movement of the lever arm 45 and an upward travel of the pin 55 in the arcuate slot 54 of the bell crank 48. The parts are so adjusted that when the wound thread has moved the finger 44 in a clockwise direction to an extent that the pin 55 enters the straight slot 53, then the bobbin is wound with the proper amount of thread. As soon as the pin 55 passes into the straight slot 53 the bell crank 48 is released for clockwise movement under the action of the tension spring 57 and, therefore, said spring functions to move the parts of the mechanism into the position shown in Fig. 3 and wherein the pulley 42 is disengaged from the belt 30 and the lever arm 45 is in its upper position. The disengagement of the pulley 42 from the belt 30 is automatic and is controlled by the amount of thread wound on the bobbin. It will be understood, however, that should the operator desire to disengage the pulley 42 from the belt 30 at any time during the winding process all that need be done is to manually move the lever arm 45 upwardly. As previously referred to the rocking of the bell crank L in either direction causes the gear 41 to roll around the gear 37.

From the foregoing description it will be seen that the bobbin winder mechanism is contained substantially entirely within the cavity of the sewing machine arm and is concealed by the cover plate 31. It will also be noted that said mechanism is in its entirety carried by the cover plate 31 and moves as a unit therewith when said plate is detached from or applied to the sewing machine arm. In addition it will have been observed that the spindle 36 on which the bobbin is mounted is on a fixed axis and does not have any to and fro movement when the bobbin winder mechanism is rendered operative or inoperative as do the bobbin carrying spindles in the usual mechanisms of this character. It will further have been noted that the disengagement of the drive to the bobbin winder mechanism is automatic and is controlled by the thread being wound on the bobbin.

Although a preferred embodiment of the invention has been illustrated and described herein it will be understood that the invention is susceptible of various modifications and adaptations within the scope of the appended claims.

Having thus described my invention, I claim:

1. In a bobbin winder mechanism for a sewing machine, a support, a spindle adapted to mount the bobbin, means carried by said support for rotatably mounting said spindle therein on an axis fixed against lateral and endwise movements, means movably carried by said support and non-rotatable with said spindle and having a driving member adapted to be engaged with and disengaged from a driving element of the sewing machine, operative connections between said driving member and said spindle, and means for moving said movably carried means to cause said engagement and disengagement of said driving member with respect to said driving element.
2. In a bobbin winder mechanism for a sewing machine, a support, a spindle adapted to mount the bobbin, means carried by said support for rotatably mounting said spindle therein on an axis fixed against lateral and endwise movements,

means rockably carried by said support and having a driving member adapted to be engaged with and disengaged from a driving element of the sewing machine, operative connections between said driving member and said spindle, and means for rocking said rockably carried means to cause said engagement and disengagement of said driving member with respect to said driving element.

3. In a bobbin winder mechanism for a sewing machine, a support, a spindle adapted to mount the bobbin, means carried by said support for rotatably mounting said spindle therein on a fixed axis, means rockably carried by said support and having a driving member adapted to be engaged with and disengaged from a driving element of the sewing machine, operative connections between said driving member and said spindle and including a gear carried by said spindle and a gear carried by said rockably carried means and rotatable with said driving member and meshing with said first named gear, and means for moving said rockably carried means to cause said engagement and disengagement of said driving member with respect to said driving element.

4. In a bobbin winder mechanism for a sewing machine, a support, a spindle adapted to mount the bobbin, means carried by said support for rotatably mounting said spindle therein on a fixed axis, means movably carried by said support and having a driving member adapted to be engaged with and disengaged from a driving element of the sewing machine, operative connections between said driving member and said spindle, and means for moving said movably carried means to cause said engagement and disengagement of said driving member with respect to said driving element and including spring tensioned means normally functioning to cause said disengagement, and means acting on said spring tensioned means to actuate the latter in a direction to cause engagement of said driving member with respect to said driving element, and means for releasably locking said spring tensioned means against normal movement in the disengaging direction.

5. In a bobbin winder mechanism for a sewing machine as defined in claim 4 and including means controlled by the amount of thread wound on a bobbin mounted on said spindle and functioning automatically to release said locking means to allow said spring tensioned means to move in the disengaging direction.

6. In a bobbin winder mechanism for a sewing machine, a support, a spindle adapted to mount the bobbin, means carried by said support for rotatably mounting said spindle therein on a fixed axis, means movably carried by said support and having a driving member adapted to be engaged with and disengaged from a driving element of the sewing machine, operative connections between said driving member and said spindle, a movable element operatively connected with said movably carried means for moving the latter to cause said engagement and disengagement of said driving member with respect to said driving element, a spring acting on said movable element to move the same and effect said disengagement, a manually operated element, and operative connections between said manually operated element and said movable element for effecting movement of the movable element against the action of said spring and in a direction to cause said engagement, said last mentioned operative connections including pro-

vision for releasably locking said movable element against movement under the action of said spring after said engagement has been effected.

7. In a bobbin winder mechanism for a sewing machine, a support, a spindle adapted to mount the bobbin, means carried by said support for rotatably mounting said spindle therein on a fixed axis, means movably carried by said support and having a driving member adapted to be engaged with and disengaged from a driving element of the sewing machine, operative connections between said driving member and said spindle, a movable element operatively connected with said movably carried means for moving the latter to cause engagement and disengagement of said driving member with respect to said driving element, a spring acting on said movable element to move the same and effect said disengagement, a manually operated element, and operative connections between said manually operated element and said movable element for effecting movement of the movable element to cause and to releasably maintain said engagement and including a cooperating pin and slot connection with said slot having an actuating portion and a locking portion.

8. In a bobbin winder mechanism for a sewing machine as defined in claim 7 and wherein there is provided means operatively interconnected with said manually operated element and contacting and moved by the thread being wound on a bobbin mounted on said spindle to move said manually operated element and displace said pin from the locking portion of said slot into the actuating portion thereof whereupon said spring acts on said movable element to move the same in a disengaging direction.

9. In a sewing machine, in combination, a gooseneck having a vertical column and a horizontal arm extending from the upper end of said column, said column including a transverse partition wall, driving means for the sewing machine located exteriorly of the transverse partition wall of said column, a closure member detachably secured to said column and located outwardly of said transverse partition wall and concealing said driving means, and a bobbin winder mechanism mounted on said closure member and removable therewith as a unit and having a driving member adapted to be operatively engaged with or disengaged from said driving means when said closure member is secured to said column.

10. In a sewing machine, in combination, a sewing machine head which is substantially hollow and is defined by fixed wall portions, driving means for the sewing mechanism, supported in part by said head with a portion of said means located exteriorly of the wall portions of the head, a removable closure member detachably secured to the head to conceal said portion of said driving means, and a bobbin winder mechanism mounted on said closure member and removable therewith as a unit and having a driving member adapted to operatively cooperate with said portion of said driving means when said closure member is secured to the head.

11. In a sewing machine, in combination, a bed plate, a gooseneck on said bed plate and having a vertical column and a horizontal arm extending from the upper end of said column, said column including a transverse partition wall, a shaft rotatably mounted in said arm and provided with a pulley, power means for driving the

sewing machine and including a pulley adjacent the lower end of said column, operative connections between said pulleys including a belt drive located exteriorly of the transverse partition wall of the column, a closure member detachably secured to the column and located outwardly of said transverse partition wall and concealing said belt drive, and a bobbin winder mechanism mounted on said closure member and removable therewith as a unit and having a driving member adapted to cooperate with said

belt drive when said closure member is secured to said column.

CHARLES E. COLEGROVE.
